CLAIM

The ornamental design for an heavy duty chipping and putting green, as shown.

DESCRIPTION

FIG. 1 is a prospective view of a heavy duty chipping and putting green showing my new design;

FIG. 2 is a front elevational view thereof, the rear being a mirror image thereof;

FIG. 3 is a top view thereof;

FIG. 4 is a left side elevational view thereof; the right side being the same in appearance; and,

FIG. 5 is a bottom plan view thereof.
